one-half to Walter W. Johnson, San Fran-
cisco, Calif.

Application February 12, 1937, Serial No. 125,452

2 Claims. (Cl. 209—157)

My invention relates to classifiers, and particularly to improvements in a device for classifying solid particles carried in a stream of liquid.

It is among the objects of my invention to provide an improved classifier particularly useful in the treatment of crushed ores, placer sands and similar materials whereby large quantities of solid material may be accurately classified in accordance with the physical properties of specific 10 gravity, size and shape, to concentrate the values to be recovered in a relatively small bulk.

Another object is to provide a classifier which may be readily and accurately adjusted for effecting a separation of solid particles in accordance 15 with a desired classification; and for adapting the device for use in the treatment of various kinds of materials.

Another object is to provide a classifier which will facilitate the recovery of values collected by 20 the riffles of sluice boxes and similar devices, and which will effectively trap and retain precious metals, amalgam, mercury, and similar values washed therefrom.

The invention possesses other objects and features of advantage, some of which, with the foregoing, will be set forth in the following description of my invention. It is to be understood that I do not limit myself to this disclosure of species of my invention, as I may adopt variant 30 embodiments thereof within the scope of the claims.

Referring to the drawing:

Figure 1 is a vertical mid-sectional view of a classifier embodying my invention, portions being broken away;

Figure 2 is a plan view, partially in section, of the embodiment shown in Figure 1, parts being broken away;

Figure 3 is a sectional view of the delivery end 40 of the classifier conduit taken in the plane of the line 3—3 of Figure 1;

Figure 4 is a sectional detail of a suitable fitting through which a flow of liquid may be introduced into the bottom of the hopper.

My invention is primarily intended for collecting gold, platinum and similar valuable materials from placer sands, crushed ores and similar materials, very large quantities of which must be handled with extreme economy in order to obtain a profitable recovery of very small quantities of the valuable substances. The problem of recovering such substances is frequently complicated by the fact that the values are present in various conditions which resist the ordinary methods of classification and recovery heretofore commonly

used. For example, gold may be coated, as in the case of "rusty" gold, or it may be in a combined form which resists or completely precludes amalgamation in the ordinary sluice boxes. Particles of value may be enclosed in grains of quartz or other gangue which are lost with the waste materials carried over the riffles of the ordinary types of classifiers; or the size, shape and buoyancy of particles, as in the case of fine flake gold, may be such as to cause the values to be carried over the riffles. The classifier of my present invention is particularly useful for concentrating such values into a relatively small bulk which can be economically treated to effect a complete recovery of the values.

In terms of broad inclusion, the classifier of my invention comprises a conduit arranged to receive a flow of liquid carrying particles of solid matter such as placer sands, crushed ores and similar materials to be classified in accordance with their specific gravity, size, shape and related physical properties. The conduit is provided with a wide shallow horizontal inlet and a deep narrow vertical outlet. The cross sectional area is made substantially equal at all points along the length of the conduit so that the velocity of a stream flowing through the conduit will be substantially uniform and free of cross or eddy currents along its entire length. The depth of the stream increases progressively along the length of the conduit, and as a consequence there is a gradual upward displacement of the major portion of the flow relative to the bottom of the conduit.

Particles of solid material carried by a stream of water flowing through the conduit tend to follow a substantially straight course except as they are affected by the opposing forces of gravity and the upward displacement of the flow due to the shape of the conduit. Under these conditions, the heavy particles tend to settle out and form a stratum across the bottom of the conduit. Particles of lighter or of more buoyant character settle out to lesser degree; and the rising flow of water tends to lift those particles and carry them over the heavier particles at various depths in accordance with physical properties of the individual particles. By the time a given volume of water flows from the inlet to the outlet the particles carried thereby will have arranged themselves in zones; and will have become segregated with other particles, having similar physical properties, in a plurality of strata extending across the width of the conduit at various depths.

This stratification of the solid particles is con-

trolled by adjusting the inclination of the conduit. Such adjustment regulates the velocity of flow, and varies the degree of the rising movement of the stream relative to the bottom of the conduit; and also varies the amount of vertical movement of the particles while being carried along the length of the conduit.

Means are provided for selectively dividing the stream issuing from the conduit into a plurality of portions corresponding to selected strata of the solid particles carried thereby; and for delivering the stream portions into separate launders, whereby the classified products may be directed to desired points where they may be further treated or disposed of in any appropriate manner.

My invention also contemplates the provision of a hopper through which the water and solid particles are delivered to the classifying conduit. Preferably, but not necessarily, the hopper is provided with current producing means for effecting a partial separation of desired substances such as heavy particles of precious metals, amalgam and mercury from the bulk of the flow before it enters the classifying conduit.

In terms of greater detail, and referring particularly to the preferred embodiment of my invention illustrated in the drawing, the classifier of my invention comprises a conduit 1 having a wide shallow inlet 2 and a narrow deep outlet 3. The sides of the conduit converge toward the outlet and are of progressively increasing height from the inlet to the outlet end of the conduit. The relation of the width and depth of the conduit is such that the cross sectional area is substantially the same at all points along the length of the conduit. This causes a stream of water passing through the conduit to flow at substantially uniform velocity along the conduit without setting up objectionable eddy or cross currents; and also causes a rise of the flow relative to the bottom of the conduit.

The shape of the conduit 1, and the proportions of its dimensions, may be varied within relatively wide limits. In general, the width of the inlet should be from about ten to fifty times its depth; and the outlet should have a depth from two to ten times its width. Satisfactory results have been produced by a conduit of the form illustrated in the drawing, the inlet being 32 inches wide and $\frac{1}{8}$ inch deep. The outlet has a width of about $1\frac{1}{4}$ inches for a distance of about 2 inches up from the bottom. Above that point, the sides may flare to a width of about 5 inches so as to reduce the height of the outflowing column of water. A conduit of this form having a length of about 8 feet has been found to be satisfactory. The length may be varied within wide limits, a greater length being desirable where the differences in the physical properties are slight, and a lesser length being satisfactory where the differences are great.

The conduit 1 may be made of any suitable material, sheet metal of a thickness of about $\frac{1}{16}$ inch and having smooth welded joints being preferred. The bottom of the conduit is preferably flat, while the sides and top of the conduit are curved to obtain the desired uniform cross sectional area. The top is preferably closed, but may be left open in installations where the inclination of the conduit is such that the flow of water does not rise above the level of the inlet 2.

The outlet end of the conduit 1 is provided with one or more delivery spouts 6 arranged to divide the outflowing stream into a plurality of portions each containing a desired stratum of the

solid particles. The spouts 6 may be in the form of a plurality of nested troughs carried by arms 7 mounted upon suitable pivots 8. The arms 7 permit the spouts 6 to be adjusted to desired positions relative to the outlet 2, suitable securing means such as a stud 9 and wing nut 10 being provided for holding the arms 7 and spouts 6 in adjusted position.

The spouts 6 are preferably adjustable relative to each other so that each may be positioned with its bottom spaced a desired distance above the bottom of the next lower spout. Studs 11 extending through slots in the sides of the inner spouts 6, and provided with wing nuts 12, provide one simple means for securing the spouts in adjusted relation, but any other suitable securing means may of course be substituted if desired.

The spouts are of progressively greater lengths, and the outer ends of the spouts 6 are arranged to deliver the respective portions of the stream into separate launders 15. The inner end of each spout 6 is provided with a thin edge for dividing the outflowing stream at a sharply defined line between adjacent strata.

Material is supplied to the conduit 1 from a launder 16 which may be the sluice box of a dredger, or a tail race or other launder arranged to deliver a flow of water and entrained solid material into the conduit. The material is supplied under sufficient head to insure that the stream will rise and substantially fill the conduit 1 at its outlet end. This is preferably accomplished by means of a hopper 17 into which the stream flows through an opening 18 in the bottom of the launder 16. A screen 19 may be mounted over the opening 18 to prevent coarse gravel and refuse from entering the hopper.

The conduit 1 is connected to the hopper 17 near its lower end by means of a flexible joint permitting pivotal adjustment of the conduit for varying its inclination. The flexible joint may be a pad 21 of rubber or other yieldable material secured around the outlet 22 of the hopper. The inlet end of the conduit 1 may be secured to the pad 21 by means of a flange 23 through which rivets or other suitable securing means may be applied.

The outer end of the conduit 1 is adjustably supported in any convenient manner, as for example by a suspension rod 24 provided with a turn buckle 25 by which the outlet end of the conduit may be raised or lowered to obtain a desired inclination.

Such adjustment of the conduit 1 permits an effective control of the stratification of the solid particles carried by the stream flowing through the conduit. This control is due in part to the change in velocity of the flow; and in part to the difference in the degree to which the flow rises above the inlet, and the difference in the degree of vertical movement of the particles. Thus, if the conduit has little or no inclination, the heavy particles have only a short distance to settle before reaching the bottom of the conduit, and are carried along as a dense strata across the bottom of the conduit. Lighter and more buoyant particles are carried upwardly by the rising flow of the water and arrange themselves in various zones depending upon their physical properties. The separation of the particles under such conditions, particularly the heavier particles forming the lower strata, is somewhat in the nature of the so-called "hindered settling," the particles being carried in a

dense mass within which the particles move relative to each other.

As the downward inclination of the conduit 1 is increased, the heavy particles have farther to sink, and there is a lessening of the degree to which the flow rises above the inlet. As a result, only the particles of greatest specific gravity and least buoyancy will reach the bottom strata, and other particles will arrange themselves in higher strata in accordance with their obvious properties. Under these conditions, separation of the particles occurs more in accordance with the principles of "free settling" wherein each particle is free to assume its proper position without material interference by other particles.

The conduit may be adjusted to any desired inclination ranging from substantially level, or even slightly upwardly inclined, to a downward inclination such that the stream does not rise above the inlet. In all positions of adjustment, classification is effected as a result of the action of the stream of water flowing through the conduit without the introduction of water from a separate source.

The various strata of the classified particles are separated as they leave the conduit 1 by the spouts 6. Since the outlet is narrow, the various strata will be relatively deep, and the spouts 6 may be readily adjusted to separate the strata at points which will insure the retention of substantially all of the values in one or more portions of relatively small volume containing a minimum of waste material.

In general, the major portion of the values will be carried in the lower stratum and may be delivered directly from the conduit 1 into a launder for directing that portion of the stream to a place for further treatment. The narrow portion at the bottom of the outlet illustrated in the drawing is ordinarily sufficient to accommodate the stratum which includes the principal values, and the lowermost spout is adjusted to divide the outflowing stream at the upper limit of the value carrying stratum. If the upper strata contain no worth while amounts of values, a single spout 6 will be sufficient and all of the portion of the stream received by the lower spout 6 may be disposed of in any convenient way. If the upper strata carry values worth recovering, additional spouts 6 are provided and adjusted to separately deliver the strata which carry the values. For example, if the condition of the valuable substance is such that it is segregated in one of the upper strata, as for example, in the case of fine flake gold which may be carried upwardly by the rising flow of the stream, the upper spouts are adjusted to separate the gold bearing stratum from the rest of the stream. Similar adjustment may of course be made for separating other strata carrying values of other kinds when desired. The location and extent of the various strata containing values worth recovering may be readily determined by analysis of the solid material segregated at various levels, and the spouts may then be adjusted accordingly.

In the classifying of dredger tailings and in similar types of service it has been found desirable to provide the hopper 17 with means for effecting an initial separation of gold, platinum, amalgam, mercury and similar heavy materials from the stream before it enters the conduit 1.

For that purpose, the hopper 17 is widened toward its bottom and is provided with a baffle 26 for directing inflowing material toward the side opposite the outlet opening 22. A flow of water is introduced into the lower portion of the hopper, at a level slightly below the outlet 22, through a supply pipe 27. The flow of water is distributed by means of a plurality of branch arms 28, each of which is provided with a plurality of outlets 29.

The outlets 29 preferably comprise upwardly extending nipples delivering the water into hoods 31, shaped to form a plurality of relatively narrow slot-like openings radially disposed around the nipples, and discharging downwardly toward the bottom of the hopper. Since the bottom of the hopper is normally closed, the water so introduced causes a flow upwardly past the outlets 29. The upward current so produced is controlled by varying the amount of water supplied, so that only particles having a very high specific gravity will sink downwardly against the force of the upward current.

The outlets 29 are spaced to obtain a substantially uniform upward current above the hoods 31; and to provide spaces through which heavy particles such as precious metals, amalgam, and mercury may settle to the bottom of the hopper. The bottom of the hopper 17 is provided with a clean-out spigot 32 through which materials collected therein may be withdrawn.

This arrangement provides an effective means for separately collecting heavy particles of value which may be washed past the riffles of a sluice. At the same time, it facilitates the collecting of values and the cleaning up of the sluice. In this connection, it is only necessary to dump the riffles and wash the collected materials along the sluice and into the hopper. The precious metals, amalgam and mercury will sink to the bottom of the hopper against the force of the upward current of water therein; and may be removed through the spigot 32. Any values which may be carried through the hopper into the classifier conduit 1 are of course collected with other values segregated by the classifier.

The provision of a separate supply of water into the hopper is of course optional, and may be omitted if desired.

I claim:

1. In a classifier, a tubular conduit of rectangular cross-section having substantially uniform cross-sectional area at all points along its length and having a wide shallow inlet and a deep narrow outlet, selector spouts arranged at the outlet end of the conduit to receive various strata of a stream flowing from the conduit, and means for adjusting the inclination of the conduit.

2. In a classifier, a conduit having a wide shallow inlet and a deep narrow outlet, the cross sectional area of said conduit being substantially the same through the length of the conduit, a hopper connected to the conduit, means for directing a stream of water and entrained solid matter into the top of the hopper for delivery to the conduit, and means in the lower portion of the hopper for introducing water into the stream within the bottom of the hopper in a substantially even upward trend for partially classifying the material prior to entry into the conduit.
